UNITED STATES PATENT OFFICE

SANFORD C. PITNEY AND GEORGE M. GARDNER, OF QUINCY, ILLINOIS,
ASSIGNORS OF ONE-THIRD TO DON A. SWEET, OF SAME PLACE.

CLAY POST.

SPECIFICATION forming part of **Letters Patent No. 558,418**, dated April 14, 1896.

Application filed October 14, 1895. Serial No. 565,654. (No model.)

To all whom it may concern:

Be it known that we, SANFORD C. PITNEY and GEORGE M. GARDNER, citizens of the United States, residing at Quincy, in the county of Adams and State of Illinois, have invented certain new and useful Improvements in Clay Posts; and we do hereby declare the following to be a full, clear, and exact description of the invention, such as will enable others skilled in the art to which it appertains to make and use the same.

Our invention relates to improvements in fence-posts; and it consists in certain novel features hereinafter described and claimed.

15 The said invention is especially intended to provide certain improvements upon the solid post described in our Patent No. 532,246, dated January 6, 1895.

Our invention will be understood by reference to the accompanying drawings, in which the same parts are indicated by the same letters throughout the several views.

Figure 1 represents a perspective view of a fence in which our improved posts are used.

25 Fig. 2 represents a section of one of the cylindrical posts made by a plane passing through its axis. Fig. 3 represents a transverse section across the post and through one of the fastening-holes. Fig. 4 represents an

30 enlarged detail view of the post with one of fastening-wires therein. Fig. 5 represents a similar device to that shown in Fig. 4, except that the ends of the fastening-wire are bent along an element of the cylindrical post; and

35 Fig. 6 represents a similar section to that shown in Figs. 4 and 5, except that the ends of the fastening-wire are bent around part of the circumference of the post.

40 A represents the post provided with the small longitudinal perforation a and the transverse perforations a^0 , which latter have their axes preferably all in the same plane with the axis of the post.

B represents the fence-wire, which may be 45 either plain, as shown, or barbed, if preferred. This fence-wire is held in place abreast each of the transverse perforations a^0 by means of the fastening-wire C. This fastening-wire is preferably in the hair-pin 50 form with an eye c. The fence-wire may be secured to the post by means of the fastening-wire in several different ways. Thus in

Fig. 4 the eye c is on one side of the post, and the two legs c' are pushed through the hole a^0 , and are twisted together outside of 55 the fence-wire B. With this mode of fastening, the eye c affords sufficient resistance to prevent the fastening-wire C from being pulled through the body of the post.

In the form of device shown in Fig. 5 the 60 same hair-pin fastening-wire C is used, but the two legs c' are slipped over the fence-wire B until the latter rests in the eye c, when the said legs are shoved through the hole a^0 , and the ends are bent up along an element 65 of the cylindrical post.

In the form of device shown in Fig. 6 the 70 same sort of fastening-wire is used, except that the ends of the legs are bent around the circumference of the post, as shown at c². The shell of the said cylinder should be of sufficient thickness to supply in itself the required strength of post, without the addition of metallic bars or other means for supplementing the inherent strength of the baked 75 clay column.

By this construction of post the well-known structural strength of a hollow column is obtained and the manufacture of the post is greatly facilitated. Thus the clay which may 80 be found in large quantities in a great many localities is simply ground and mixed in the ordinary way and is then forced through a die that forms the post all ready for drying and burning except for the simple act of 85 making the perforations a^0 , which latter should be done before the clay post is baked. Furthermore, in the process of baking the heat can be supplied to both sides of the shell, and only has to penetrate one-half of 90 the thickness of said shell. The result is a much more uniform hardness and better cohesion of particles in the post of the hollow-column construction than in one of the solid-column construction, as described in our patent 95 aforesaid.

A post of this construction may be run out continuously through a die and then cut up into any desired length, whereby great economy in the cost of manufacture is secured. 100

After baking, the post is more or less rough on its exterior, and holds very well when set to the proper distance in the ground, without the necessity for anchors, flanges, or other

auxiliary means for holding the post in the ground.

The thickness of the shell of the post should be such that the baked clay will be strong enough in itself to resist all the strains to which in ordinary usage the post would be subjected, and should also be of sufficient thickness to resist accidental fracture under conditions likely to occur.

10 It will be obvious that by the herein-described construction a simple, strong, cheap, and efficient post is provided, made out of baked clay which is practically indestructible for analogous purposes.

15 This post may be made large and heavy, as for gate-posts, or light, as for grape-vine trellises, or of intermediate size and strength, as for ordinary fences.

20 The various other advantages of the herein-described structure will readily suggest themselves to any practical mind.

Having thus described our invention, what

we claim, and desire to secure by Letters Patent of the United States, is—

The combination with a fence-post made of baked clay and in the form of a hollow cylinder provided with transverse perforations, extending through both sides of the post, of fence-wires, and fastening-wires in the form of a hair-pin, but with an eye at the junction 3c of the legs, the said legs being passed through said transverse perforations, and said eye engaging in rear of the fence-post while the said legs are adapted to be twisted around and to hold one of the said fence-wires, substantially as described.

In testimony whereof we affix our signatures in presence of two witnesses.

SANFORD C. PITNEY.
GEORGE M. GARDNER.
